AIRCRAFT RADIO ANTENNA

William C. Rogers, 5365 NW. 36th St.,
Miami Springs, Fla. 33166

Filed May 5, 1967, Ser. No. 6,963

Term of patent 14 years

(Cl. D26—14)

FIG. 1

FIG. 4

FIGURE 1 is a perspective view of an aircraft radio antenna according to the embodiment of my inventive design;

FIGURE 2 is a view of one side of the aircraft radio antenna shown in FIGURE 1 and is the same as the view from the other side thereof;

FIGURE 3 is a top view of the aircraft radio antenna shown in FIGURE 1;

FIGURE 4 is an end view of the aircraft radio antenna shown in FIGURE 1; and

FIGURE 5 is a cross-sectional view of a portion of the aircraft radio antenna shown in FIGURE 1 taken along the lines 5—5 therein.

The characteristic feature of the design resides in the bullet shaped body of revolution effecting a smooth blend between the cantilevered slender rod and the rearwardly swept aerofoil section, main member.

I claim:

The ornamental design for an aircraft radio antenna, substantially as shown and described.
